HEATING FURNACE

Thomas W. Torr, Dowagiac, Mich., assignor to
Rudy Furnace Company, Dowagiac, Mich., a
corporation of Michigan

Application March 1, 1941, Serial No. 381,307

6 Claims. (Cl. 126—116)

This invention relates to improvements in heating furnaces.

The main objects of my invention are:

First, to provide a warm air furnace of steel construction which is substantially free from "hot spots" in the radiating surface thereon, the latter being maintained at a practically uniform temperature throughout its surface and thereby giving a more efficient delivery or transfer of heat to the air stream passing the outer surface thereof.

Second, to provide a steel furnace of the character described wherein by reason of the uniformity of distribution of heat to the radiating surface thereof the noises generally accompanying expansion and contraction in steel furnace construction are substantially eliminated.

Third, to provide an equalized heat distribution construction for a warm air furnace wherein the heat evolved is prevented from passing in a direct and rapid stream to the fluid outlet, thereby providing for a long hold-over of heat in the furnace and preventing a condition wherein the furnace is permitted to cool below the desired temperature in its intermittent operation, this condition being sometimes referred to as "cold 70's," thus enabling frequent fan operations after the burner is shut off and maintaining greater fuel economy.

Fourth, to provide a steel furnace of the type described wherein the total required radiator surface for a given heat input is substantially decreased thereby compacting the furnace as a whole, and in which the said surface is uniformly heated at a relatively low temperature throughout the entire surface thereof, with resultant improvement or increase in efficiency.

Fifth, to provide an oil burning furnace of the type described which operates at high efficiency regardless of the input of oil fed thereto or the capacity of nozzle utilized to thereby provide a furnace of widely variable output or capacity with uniformly high efficiency.

Sixth, to provide an oil burning furnace of the character described which is free from fluttering or pulsations at the commencement of operation thereof regardless of the back pressure thereon.

Further objects relating to details and economies of my invention will appear from the description to follow. The invention is defined in the claims.

A structure embodying the features of my invention is illustrated in the accompanying drawing, wherein:

Fig. 1 is a fragmentary view in side elevation

illustrating a furnace in accordance with my invention, the details of the equalized heat distribution and radiating structure being conventionally indicated in dotted lines to show the relative positioning thereof in the furnace shell or casing.

Fig. 2 is a fragmentary view in front elevation partially broken away and in vertical section, the furnace casing being largely removed, illustrating the construction and relation of the radiating surface and the heat distributing structure associated with the combustion chamber of the furnace in accordance with my invention.

Fig. 3 is a fragmentary top plan view, being partially broken away and in section on line 3—3 of Fig. 2, further illustrating the relation of the parts.

Referring to the drawing, reference numeral 1 indicates a suitable rectangular furnace casing having opposed side walls and front and rear walls surrounding the heat generating, distributing and radiating structure of my furnace, which structure is generally indicated by reference numeral 2. The latter includes as the outer element thereof the upright rectangular steel radiator shell 3 which is practically coextensive in height with the furnace and is closed at its top. This shell is separated from the furnace casing 1 by an air circulating space 4 communicating with the interior of the dome 5 for the casing into which the various hot air ducts 6 are led. The shell 3 includes a removable front plate 5 bolted thereon and readily removable for access to the remainder of the parts disposed interiorly of the shell.

As illustrated in Fig. 2, the radiator shell 3 has secured thereto at the side thereof a plurality of braces 26 which hold in place a refractory combustion chamber 7 in which the oil burner unit 8 is disposed, see Fig. 1, this unit being supplied with suitable connections 9.

The braces 26 further serve as supports for a primary elongated rectangular steel equalizer member 10 which extends for a substantial distance above the braces vertically in the radiator shell 3, being spaced a substantial distance from the four sides thereof.

Telescopingly surrounding the aforesaid equalizer member 10 and sustained on the shell 3 by means of brackets 11, and likewise secured to the equalizer member by the further brackets 12, is the secondary equalizer member 13 which is of steel in rectangular sectional outline, closed at its top. This secondary equalizer is inverted over the equalizer member 10, extending for a sub-

stantial distance downwardly lengthwise toward the bottom of the latter.

The aforesaid construction provides a relatively lengthy and tortuous path for the products of combustion from oil burner 8. They must first rise up through the primary equalizer member 10 transferring heat thereto and being distributed around its perimeter, then travel downwardly all around the space surrounding the said member between the same and the secondary equalizer member 13. This effects a substantial and uniform distribution of the hot products of combustion and the transferred heat units. Following the aforesaid downward travel, the products of combustion must travel upwardly through the space surrounding the secondary member 13 between the same and the radiator shell 3 on the side of the shell 3 opposite from the flue 14, there being an opposite movement downward of the burned gases between the equalizer member 13 and the shell 3 on the side of the shell 3 in which the opening to flue 14 is located. This furthers and completes the distribution of heat in uniform manner over the inner surface of the radiator shell 3. Heating units are picked up from the latter by air circulated past the outer surface thereof in space 2 by a fan (not shown).

Subsequent to traversing the inner walls of the radiator shell 3, the products of combustion pass outwardly through a flue 14 disposed at a relatively low point in the shell into a heat exchanger 15 disposed behind the radiator shell, thence outwardly from the furnace casing through the flue 16 to the stack.

In the operation of the foregoing furnace construction all intensely hot spots on the radiating surface or shell 3 have been eliminated. At the same time, portions of this surface which would ordinarily be of lower temperature than the heat equalizer members 10, 13 so spread the heat over the entire surface of the radiator shell by reason of its dissemination in circulating through the equalizers that it is held at a practically uniform temperature, thereby giving a much more efficient delivery of heat into the air stream circulating between the said shell and the furnace casing 1. This obviates the excessive and noisy expansion and contraction which have heretofore been generally found in steel constructed furnaces wherein the surfaces are unequally heated.

Moreover, in the foregoing furnace construction not only is the flow of gases directed so as to equalize and distribute heat over the radiator in an even manner, but the latter are heated at a considerably lower temperature than would otherwise be possible. The temperature of the radiator shell does not often exceed 500°, making the transfer of heat from the shell to the air stream a very efficient one. It is a long established fact that in direct fired furnaces, i. e., those in which air passes over the hot surfaces, the radiating surfaces are very much more efficient at temperatures around 400° or 500° than they are at higher temperatures of 700° or 800°.

I desire to emphasize the fact that in my construction neither one of the equalizer members 10, 13 is located in the air stream. These equalizers are not merely for the purpose of deflecting or directing the flow of gases, but, more definitely, they are decidedly for the purpose of equalizing and distributing the temperature over the inside of the enclosing radiating shell therefor, which latter is adjacent an external air stream, to the end that the heat which is transferred to

the air stream will be so transferred uniformly at all points at which the stream impinges the radiator shell and, moreover, at a relatively low temperature in the interests of efficiency of transfer. I consider that it is in this respect that my system distinguishes primarily from previous efforts in this art. Perhaps it is because of this distinguishing feature that the economy of construction and simplicity of the herein described furnace results. All previous attempts to increase the efficiency of heat transfer by air circulation past radiating surfaces, for example, in the use of a number of small tubes heated interiorly by combustion gases and having air circulating, around them, or employing means for circulating air on one side of the number of furnace pipes on the opposite side of which the flue gas is caused to flow, are uniformly complicated and expensive in construction. This can certainly not be said of the present design.

A prominent characteristic of the flue gas heat equalizer furnace which I have described is the slowness with which the heat is passed through the outer radiating surface or shell with resultant maintenance of the air stream externally of the shell at a satisfactory temperature for a substantial period of the time after the burner has been shut off. "Cold 70's" are eliminated, an end that every manufacturer of steel furnaces has attempted to achieve. Due to this equal distribution of heat by the equalizer member, the stack temperature goes up very slowly and, for the same reason, drops very slowly after the burner is shut off. This slow and even rise and fall of the stack temperature I find establishes a very definite relation between stack temperature and the temperature in the warm duct. There is a ratio of approximately one to seven between the duct temperature and the stack temperature, i. e., when the furnace is in normal operation for average winter weather, which presumes that the burner will be on half the time and off half the time at more or less regular intervals. If the temperature of the stack rises seven degrees, there will be a rise of one degree in the temperature of the air in the warm air duct. When there is a drop of seven degrees, there will be a drop of one degree. As an example, derived from the operation of a furnace as described, with an operation of the burner over a period of several hours varying from seven to nine minutes at a time, and an "off" time of the burner varying from eight and a half to nine minutes, an average stack temperature during the "on" operation of the burner is about 468° with a duct temperature averaging 145°. During the "off" period of the burner, the stack temperature receded to an average temperature of 295° and the average duct temperature is 120°.

This means that the present design accomplishes a very desirable result by a very simple construction, in that, without the use of a two-speed fan or a high and low burner arrangement there is provided in an average winter weather a continuous fan operation with a very slight variation in duct temperature, maintaining a uniform temperature in a heated room supplied by the furnace.

Another advantage of the structure of the present invention is the range of capacity which is made possible without affecting in a material manner the efficiency of operation. Thus, the operation described in the preceding paragraphs was obtained with a 1.35 gallon nozzle. With a 1 gallon nozzle, the only change resulting is an

approximately 25° reduction in stack temperature during the operation of the burner. The efficiency is not affected more than one or two per cent, which, owing to the high inherent efficiency of the burner itself, is negligible. A wide input range is available adapting a furnace for varying installation or demand, which is a great advantage to the dealer in reducing the variety of his stock for one size furnace will suffice for a great majority of his installations, ranging from 8-10 room houses up to 12 or 14 rooms.

Tests comparing the performance of the equalized furnace structure described above with other types now on the market illustrate clearly the enhanced efficiency of the former, likewise the fact that for a given heat input the required radiating surface is substantially decreased, thereby satisfying a pronounced recent trend in the design of furnaces of smaller size. There is a substantial demand on the part of the public for smaller furnaces occupying less space in a basement.

In the aforesaid tests three furnaces were used. Furnace A was of the cast iron, direct heating radiator type in which the flue gases are caused to travel vertically being horizontally baffled during the travel, and in which the air is circulated directly over the outer radiating surface of the element. This furnace had a heat input of 80,000 B. t. u. and requires 49 sq. ft. of radiating surface. Furnace B was a steel tube, direct radiation type having a 65,000 B. t. u. input and in which the flue gases are circulated vertically through a plurality of steel spaced tubes with the air to be heated in direct external contact with the tubes. The requisite heating surface of this furnace is 29.6 sq. ft. Furnace C was a heat equalizer type in full accordance with the foregoing disclosure with a heat input of 65,000 B. t. u., which however required but 20 sq. ft. of radiating surface.

The operating data of the above three furnaces are set forth, for purposes of clarity, in tabulated form in the following chart, in which the radiating surface of furnace A has been expressed twice, i. e., for its actual 80,000 B. t. u. input and for a theoretical input equal to the heat input of the other two furnaces tested.

nace is in its complete elimination of pulsations during initial operation. This is one of the factors which has seriously annoyed the furnace designer and is still a source of trouble to manufacturers. At the commencement of operation of many oil furnaces, when the latter are cold, there is apt to be a flutter or pulsation until the furnace becomes warm. If the flue conditions are such that there is any back pressure at all on the furnace, such pulsations are sure to result, in more or less aggravated degree. I have found that a furnace as described above, due to its uniform equalized distribution of and transfer of heat to the air, can be operated with as much as 15 1/2 inch back pressure without any tendency whatever to pulsate.

While the structure illustrated is an embodiment of my invention in an oil burning furnace, it will be understood that it is as well adapted for use in a gas burning furnace and is further desirable for use with solid fuel, although of particular merit with gas or liquid fuel.

I have illustrated and described the features of my invention in an embodiment which is very practical. I have not attempted to illustrate or describe other embodiments or adaptations as it is believed this disclosure will enable those skilled in the art to embody or adapt my invention as desired.

Having thus described my invention, what I claim as new and desire to secure by Letters Patent is:

1. An oil burning furnace of steel construction comprising an elongated vertical steel radiator shell providing a heat radiating surface of substantial area, said shell being substantially co-extensive in height with the furnace, a plurality of brackets mounted interiorly of said shell, said radiator shell having a refractory combustion chamber disposed therein at the base thereof and positioned by said brackets, said combustion chamber having an oil burner therein, a first hollow open ended steel equalizer member located centrally in said shell above said combustion chamber and supported on said brackets, said member extending vertically for a substantial distance in said shell and directing products of

Style	B. t. u. heat input	Net stack temp.	Sq. ft. radiating surface	B. t. u. heat input per sq. ft. radiating surface	Per cent saving in radiating surface
A—Cast iron direct radiation.....	{ 80,000 65,000 }	475	{ 49 39.8 }	1,633	
B—Steel tube direct radiation.....	65,000	475	29.6	2,200	25.6 over A
C—Equalizer type.....	65,000	475	20	3,250	47.2 over A (32.4 over B)

Comparing the performance of the foregoing three types of heating elements, it is seen that while furnace B, as compared with furnace A, effects a saving of 25.6% in radiating surface required, the equalizer type furnace C involves a saving of 32.4% over furnace B and 47.2% over furnace A.

In these comparative tests all conditions of room temperature, firing, etc., were similar. The results clearly indicate that substantial saving in cost of material and overall dimension is made possible by the above described equalizer radiator construction, in addition to the equalization of heat distribution and enhanced efficiency characterizing the same.

A still further advantageous feature of my fur-

60 combustion from said burner upwardly in the shell, a second hollow steel equalizer member having a closed top in spaced relation to the top of the first member and vertically extending sides of substantial length telescopingly associated with said first member with the sides of said members overlapping one another for a substantial vertical distance and laterally spaced from one another, said second member terminating short of the bottom of the first member and being spaced substantially from the sides of said shell to define an annular, vertically elongated downward path for the circulation of products of combustion between said members and an annular, vertically elongated upward and downward paths 65 between said second member and radiator shell

whereby the heat from the products of combustion is substantially equalized in intensity and distributed over the annular inner surface of said shell following its circulating movement, through the members, said shell having a flue opening disposed substantially on a level with the lower end of said second equalizer member, a heat exchanger having vertically spaced flue openings, the lower of which is connected to said flue opening in the shell and the upper of which is for exit of burned gases therefrom and a furnace casing surrounding and enclosing said shell and heat exchanger to define an air space surrounding the latter for the circulation of air over the external surface only of the shell and heat exchanger to effect transfer of heat from the shell thereto, the space interiorly of said shell and heat exchanger circulating products of combustion exclusively.

2. A furnace construction comprising an elongated vertical steel radiator shell providing a heat radiating surface of substantial area, said shell being substantially coextensive in height with the furnace, said radiator shell having a refractory combustion chamber disposed therein at the base thereof, said combustion chamber having a heat generating device therein, a first hollow open ended steel equalizer member located centrally in said shell above said combustion chamber, said member extending vertically for a substantial distance in said shell and directing products of combustion from said device upwardly in the shell, a second hollow steel equalizer member having a closed top in spaced relation to the top of the first member and vertically extending sides of substantial length telescopingly associated with said first member with the sides of said members overlapping one another for a substantial vertical distance and laterally spaced from one another, said second member terminating short of the bottom of the first member and being spaced substantially from the sides of said shell to define an annular, vertically elongated downward path for the circulation of products of combustion between said members and an annular, vertically elongated upward and downward paths between said second member and radiator shell whereby the heat from the products of combustion is substantially equalized in intensity and distributed over the annular inner surface of said shell following its circulating movement, through the members, said shell having a flue opening disposed substantially on a level with the lower end of said second equalizer member, a heat exchanger having vertically spaced flue openings, the lower of which is connected to said flue opening in the shell and the upper of which is for exit of burned gases therefrom and a furnace casing surrounding and enclosing said shell and heat exchanger to define an air space surrounding the latter for the circulation of air over the external surface only of the shell and heat exchanger to effect transfer of heat from the shell thereto, the space interiorly of said shell and heat exchanger circulating products of combustion exclusively.

3. A furnace construction comprising an elongated vertical radiator shell providing a heat radiating surface of substantial area, said shell being substantially coextensive in height with the furnace, said radiator shell having a refractory combustion chamber disposed therein, said combustion chamber having a heat generating device therein, a first hollow open ended equalizer member located centrally in said shell above said

combustion chamber, said member extending vertically for a substantial distance in said shell and directing products of combustion from said device upwardly in the shell, a second hollow equalizer member having a closed top in spaced relation to the top of the first member and vertically extending sides of substantial length telescopingly associated with said first member with the sides of said members overlapping one another for a substantial vertical distance and laterally spaced from one another, said second member terminating short of the bottom of the first member and being spaced substantially from the sides of said shell to define an annular, vertically elongated downward path for the circulation of products of combustion between said members and an annular, vertically elongated upward and downward paths between said second member and radiator shell whereby the heat from the products of combustion is substantially equalized in intensity and distributed over the annular inner surface of said shell following its circulating movement, through the members, said shell having a flue opening disposed substantially on a level with the lower end of said second equalizer member, a heat exchanger having vertically spaced flue openings, the lower of which is connected to said flue opening in the shell and the upper of which is for exit of burned gases therefrom and a furnace casing surrounding and enclosing said shell and heat exchanger for the circulation of air to be heated thereover.

4. An oil burning furnace of the type described, comprising a combustion chamber, a first hollow, vertically extending, open ended equalizer member disposed concentrically of said chamber and in communication therewith, said member extending for a substantial distance vertically of the furnace, to circulate products of combustion upwardly from the chamber, a second equalizer member having a closed top in vertically spaced relation to the top of the first member, said second member surrounding said first member and terminating adjacent but short of the bottom thereof with a substantial vertical overlap of the walls of the members to provide an annular passage of substantial circumference and length for the circulation of products of combustion downwards from the top of said first member, and a radiator shell surrounding and encasing said members and combustion chamber in spaced relation thereto, said shell providing an annular passage of substantial circumference and vertical height between said second equalizer member and the shell for the circulation of products of combustion passing around the lower end of the second member, said first and second equalizer members uniformly distributing annularly the heat of the products of combustion during circulation thereof whereby the heating units are uniformly transferred to the inner surface of said shell, said shell having a flue opening disposed substantially on a level with the lower end of said second equalizer member, a heat exchanger having vertically spaced flue openings, the lower of which is connected to the flue opening in the shell and the upper of which is for exit of products of combustion, and a furnace casing enclosing said shell and heat exchanger for circulation of air to be heated thereover.

5. In a heating furnace, the combination of a combustion chamber including an upright upper portion of rectangular horizontal sections and of uniform dimension from end to end and having an unobstructed discharge at the top thereof,

an intermediate member closed at its upper end and disposed in embracing concentric relation to said upper portion of said combustion chamber to receive the heated gases and products of combustion discharged from the top of said combustion chamber and coacting therewith to provide an annular down-flow space surrounding said upper portion of said combustion chamber, the capacity of said space being such that normally the heated gases and products of combustion travel in a uniform downward flow around the combustion chamber to be discharged at the lower end of said intermediate member, a radiator shell sealed against admission of external air disposed in concentric embracing relation to said intermediate member to receive the heated gases and products of combustion discharged from the lower end thereof, the capacity of the space between said intermediate member and radiator shell being such as to insure a substantially uniform distribution of the heated gases and products of combustion throughout the space as they flow upwardly and downwardly therein, said shell having a flue opening therein disposed substantially on a level with the lower end of said intermediate member, and a hot air casing surrounding said radiator shell.

6. In a heating furnace, the combination of a combustion chamber including an upright up-

per portion having an unobstructed discharge at the top thereof, an intermediate member closed at its upper end and disposed in embracing concentric relation to said upper portion of said combustion chamber to receive the heated gases and products of combustion discharged from the top of said combustion chamber and coacting therewith to provide an annular down-flow space surrounding said upper portion of said combustion chamber, the capacity of said space being such that normally the heated gases and products of combustion travel in a uniform downward flow around the combustion chamber to be discharged at the lower end of said intermediate member, a radiator shell disposed in concentric embracing relation to said intermediate member to receive the heated gases and products of combustion discharged from the lower end thereof, the capacity of the space between said intermediate member and radiator shell being such as to insure a substantially uniform distribution of the heated gases and products of combustion throughout the space as they flow upwardly and downwardly therein, said shell having a flue opening therein disposed substantially on a level with the lower end of said intermediate member, and a hot air casing surrounding said radiator shell.

THOMAS W. TORR.
